Primary Examiner — Eric Goodman*Assistant Examiner* — Luqman McNeil(74) *Attorney, Agent, or Firm* — Patent Portfolio Builders PLLC(57) **CLAIM**

The ornamental design for a remote control device, as shown.

DESCRIPTION

FIG. 1 is a left top perspective view of a remote control device showing our design;

FIG. 2 is a left side view thereof;

FIG. 3 is a right side view thereof;

FIG. 4 is a top view thereof;

FIG. 5 is a bottom view thereof;

FIG. 6 is a rear view thereof; and,

FIG. 7 is a front view thereof.

1 Claim, 4 Drawing Sheets(56)
